GASOLINE STRAINER

Filed Oct. 29, 1928

UNITED STATES PATENT OFFICE.

FRANK HELMAN, OF SCAMMON, KANSAS.

GASOLINE STRAINER.

Application filed October 29, 1928. Serial No. 315,781.

The present invention relates to a gasoline strainer and has for its prime object to provide a structure which may be mounted in the inlet neck of the gasoline tank in such a manner as to be easily removed therefrom.

Another important object of the invention resides in the provision of a strainer of this nature having its parts arranged in an exceedingly compact manner and capable of ready assembly and disassembly.

A still further very important object of the invention resides in the provision of a strainer of this nature which is simple in its construction, inexpensive to manufacture, and thoroughly efficient and reliable in use.

With the above and numerous other objects in view as will appear as the description proceeds, the invention resides in certain novel features of construction, and in the combination and arrangement of parts as will be hereinafter more fully described and claimed.

In the drawing:

Figure 1 is a sectional view of the strainer showing the same in the filling neck of a gasoline tank such as used on an automobile.

Figure 2 is a longitudinal section through the strainer portion per se.

Figure 3 is an end elevation thereof, and

Fig. 4 is a detailed view showing the method of holding the screen in place.

Referring to the drawing in detail it will be seen that the numeral 5 denotes an ordinary gasoline tank such as are used on automobiles and this tank is provided with a filling neck 6 of conventional formation. A tube 7 has a close sliding fit in the neck 6 and at its upper end is reduced and externally threaded as at 8 while the inner end thereof is internally threaded as at 9.

40 A tubular extension 10 is threaded on the upper end of the tube 7 and has an enlarged end portion 11 which is externally threaded to receive a cap 12 so that the cap may be removed and the gasoline hose nozzle easily inserted into the extension and tube. The tube is held tightly in place by means of a union 14 threaded on the neck 6 and formed with an inturned flange 15 for holding a gasket 16 in place circumjacent the tube 7 on the upper end of the neck 6.

The strainer proper is illustrated to advantage in Figure 2 and includes a sleeve 18 internally threaded at its ends to engage over rings 19 and 20. Disks 21 of foraminous ma-

terial are secured in the rings 19 by collars 22 threadedly engaged therein and at their inner edges formed with notches 23 so that a suitable implement may be engaged therewith.

The ring 19 at its upper end is externally threaded as at 25 to engage with threads 9. From the above detailed description it will be seen that when the tank 5 is to be filled the cap 12 will be removed and the hose nozzle inserted in the extension 10, the enlargement 11 affording easy access thereto and the gasoline will flow down through the tube 9 and pass through the strainer disks 21. It will further be noted that by unscrewing the union 14 the tube 7 may be easily removed and when removed the strainer parts may be readily disassembled to clean the strainer disks and then readily assembled.

It is thought that the operation, utility and advantages of this invention will now be quite apparent to those skilled in this art without a more detailed description thereof. In addition to the practical advantages hereinbefore set forth my novel gasoline strainer is obviously simple, strong and durable.

I have entered into a detail description of the construction and relative arrangement of the parts embraced in the present and preferred embodiment of my invention in order to impart a full, clear and exact understanding of the said embodiment.

I do not desire, however, to be understood as confining myself to the specific construction and relative arrangement of parts inasmuch as in the future practice of the invention, various changes and modifications may be made such as fall within the scope of my invention as defined in my appended claim.

Having thus described my invention, what I claim as new is:

A device of the class described including a filling tube in combination with a strainer structure threaded in the inner end of the tube, said strainer structure comprising a sleeve, rings threadedly engaged in the ends of the sleeves, discs of foraminous material in the rings, and means for detachably holding the discs in place, one of the rings being threadedly engaged in the inner end of the tube.

In testimony whereof I affix my signature.

FRANK HELMAN.
